Des. 202,978
Patented Nov. 23, 1965

202,978

HEADBOARD FOR A BED

Norman N. Hekler, High Point, N.C., assignor to Worth Furniture, a Division of Gravely Furniture Co., Inc., Martinsville, Va., a corporation of Virginia

Filed Nov. 10, 1964, Ser. No. 82,540

Term of patent 3½ years

(Cl. D5—4)

FIG. 1 is a perspective view of my new design for a headboard for a bed, showing my new design; and

FIG. 2 is a top plan view thereof.

The back of the article is conventionally plain.

I claim:

The ornamental design for a headboard for a bed, as shown and described.
